CEMETERY VASE

Myron E. Hunt, Indianapolis, Ind.

Application April 18, 1938, Serial No. 202,681

6 Claims. (Cl. 47—41)

This invention relates to a cemetery vase, the type commonly employed in connection with graves where it is sunk in the ground for the retention of flowers.

5 The principal object of the invention is to provide a vase which will eliminate the difficulties heretofore experienced in vases of this general type and for this use. In such vases it has been customary to provide a casing which is imbedded in the ground adapted to receive a removable flower containing vase having a closed bottom and a flange which will permit of its being inverted when no flowers are contained therein. However, in either position, water and silt will 10 seep into the casing from about the vase so that the lower portion thereof becomes damp and muddy and gradually builds up an obstruction of mud and silt. This is not only detrimental to both the casing and the vase but prevents 15 the vase from properly seating in position until and unless the mud and silt is cleaned out, which is difficult to do.

The principal feature of this invention resides in the provision of a drainage structure at the top 25 of the casing which will prevent seepage of water and silt into said casing whereby the casing will be maintained free of clogging and obstructing sediment. This is accomplished by providing a wedge-shaped supporting ring of such form as 30 to effect outward radial drainage of water and silt which otherwise would pass between the spaced walls of the casing and vase.

Another feature of the invention resides in the provision of an identifying name plate secured to the closed end of the vase so as to be exposed when the vase is in inverted position.

Other objects and features of the invention will be understood from the accompanying drawing and the following specification and claims:

40 Fig. 1 is a plan view of the structure showing the vase in open position. Fig. 2 is a section taken on the line 2—2 of Fig. 1. Fig. 3 is the same as Fig. 1 showing the vase in inverted position with the name plate exposed. Fig. 4 is a side elevation of the structure with the vase in inverted position having a central vertical section thereof cut away.

In the drawing there is illustrated a cemetery vase comprising an outer casing 10 having an open bottom end 11 and a flanged upper end 12. 50 The casing is adapted to be sunk into the ground with the flange 12 flush with the ground surface. Removably mounted within the casing 10 there is a cylindrical vase 13 closed at one end by a bottom section 14 and open at the other or upper end. 55 The vase is adapted to seat within the

(Cl. 47-41)

casing so that its bottom and side walls are spaced therefrom. The vase is freely suspended within the casing by a supporting ring 15 adapted to seat upon the flange 12. The vase is freely slideable through the ring but retained therein and supported thereon by a lower flange 16 and an upper flange 17 formed radially outward from the respective ends of the vase.

The ring 15 is formed wedge-shaped in cross section so that both sides of the ring converge or slope toward each other from the inner portion to the outer periphery. By reason of this wedge-shaped construction, either surface of the ring which is uppermost will provide a watershed. Thus, the downwardly and outwardly sloping surface of said ring will convey the water away from the vase when in its upright position, as shown in Fig. 2, as well as when it is in its inverted position, as shown in Fig. 4. 10 15

The inner edge of the ring is provided with a seat 18 on both sides thereof for reception of the flanges 16 and 17 respectively, the respective flanges being formed to slope downwardly and outwardly to conform to the sloping surface of the ring. The ring may further be provided with outwardly and radially extending drainage grooves 19 and 20 spaced about the opposite sides thereof in staggered relation, as indicated in full and dotted lines in Figs. 1 and 3. The seats 18 are flush with the respective drainage grooves 19 and 20 so that any water seeping between the flanges of the vase and the ring will drain from the ring along the grooves.

The flange 12 of the casing is provided with a peripheral groove 21 forming a gutter surrounding the edge of the ring for receiving water drained therefrom and permitting it to flow to spouts 22. This permits of the flange having a peripheral lip 23 extending upwardly flush with the periphery of the ring for centering the ring and vase within the casing. 35 40

The closed or bottom end 14 of the vase is depressed to receive and center therein a name plate 24 which may be suitably engraved as indicated and secured in position by any suitable means, that shown herein comprising a screw 25 extending through the bottom end 14. Such plate may be pressed in position or secured in any other suitable manner. In ring 15 in Fig. 1 are arcuate recesses 26 wherein the name of the manufacturer may be embossed.

In the foregoing, it will be noted that the vase 13 may be inverted and supported within the casing in either position by causing the ring 15 to slide from one end to the other into engagement 55

with the flanges 16 and 17 respectively. The ring and vase will be supported in centered position by the lip 23 on the flange 12. Regardless of the position of the ring by reason of the position 5 of the vase, it will effect a drainage of water and silt from about the vase to be discharged outwardly from the flange of the casing so as to retain the space between the casing and vase free from water and silt.

10 The invention claimed is:

1. A cemetery vase having a casing adapted to be sunk into the ground, an outwardly extending flange formed about the top of said casing having a drainage groove and spout associated therewith, a removable and reversible vase open at one end and closed at the other adapted to be mounted within said casing, outwardly extending flanges formed on opposite ends of said vase, and a supporting ring slidably mounted about 15 said vase movable between said flanges for suspending said vase in spaced relation to said casing from either end thereof, said ring having an outwardly and downwardly sloping drainage surface for draining water from about said vase 20 onto the flange of said casing.

2. A cemetery vase having a casing adapted to be sunk into the ground, an outwardly extending flange formed about the top of said casing having a drainage groove and spout associated therewith, a removable and reversible vase open at one end and closed at the other adapted to be mounted within said casing, outwardly extending flanges formed on opposite ends of said vase, and a supporting ring slidably mounted about 25 said vase movable between said flanges for suspending said vase in spaced relation to said casing from either end thereof, said ring having an outwardly and downwardly sloping drainage surface for draining water from about said vase 30 onto the flange of said casing.

3. A cemetery vase having a casing adapted to be sunk into the ground, an outwardly extending flange formed about the top of said casing having a drainage groove and spout associated therewith, a removable and reversible vase open at one 35 end and closed at the other adapted to be

mounted within said casing, outwardly extending flanges formed on opposite ends of said vase, and a supporting ring slidably mounted about 5 said vase movable between said flanges for suspending said vase in spaced relation to said casing from either end thereof, said ring having an inner peripheral seat on both sides thereof for receiving and centering the respective flanges of the vase, from which outwardly and downwardly directed drainage grooves extend for 10 draining water therefrom onto the flange of said casing.

4. A cemetery vase having a casing adapted to be sunk into the ground, an outwardly extending flange formed about the top of said casing having a drainage groove and spout associated therewith, a removable and reversible vase open at 15 one end and closed at the other adapted to be mounted within said casing, outwardly extending flanges formed on opposite ends of said vase, 20 and a supporting ring slidably mounted about said vase movable between said flanges for suspending said vase in spaced relation to said casing from either end thereof, said ring having a radial drainage groove on each side adaptable 25 to terminate adjacent the drainage spout on the flange of said casing for removing water accumulating about the top of said vase.

5. A cemetery vase having a casing adapted to be sunk into the ground, on outwardly extending 30 flange on said casing having a drainage groove and spout associated therewith, and a ring, wedge-shaped in cross section, seating on said flange for supporting a vase within said casing, said ring having a radial groove on each side 35 terminating adjacent the spout in said flange.

6. A cemetery vase having a casing adapted to be sunk into the ground, an outwardly extending flange on said casing having a drainage groove and spout associated therewith, and a ring seating on said flange for supporting a vase in said casing from either end, said ring being formed wedged-shaped in cross section to drain water accumulating about the top of the vase into said 40 groove and out of said spout irrespective of which 45 end of said vase is uppermost.
